DOUBLE LAP SEAM FELLING MACHINE

Frank A. Kucera, Chicago, Ill., assignor to Union
Special Machine Company, Chicago, Ill., a cor-
poration of Illinois

Application November 2, 1934, Serial No. 751,219

6 Claims. (Cl. 112—142)

The invention relates to new and useful improvements in a sewing machine for fell seam-
ing and more particularly to the means for guid-
ing and directing the folded edge portions of the
5 fabric sections to the needles.

An object of the invention is to provide a
machine of the above type wherein means is
provided for positively directing and guiding the
10 folded edge portions of the respective fabrics so
that the needles will pass through the respective
folded edge portions at a uniform distance from
the edge of the folded edge portions.

A further object of the invention is to pro-
vide a machine of the above type wherein the
15 throat plate is provided with means for guiding
the folded edge portion of the under fabric sec-
tion while the presser foot is provided with means
for guiding the folded edge portion of the upper
fabric section.

20 A still further object of the invention is to
provide means cooperating with the guiding
means on the throat plate for holding the folded
edge of the under fabric section in contact with
25 said guiding means. A still further object of the
invention is to provide a machine of the above
type with means for positively holding the folded
edge portion of the upper fabric section in con-
tact with the guiding means on the presser foot.

These and other objects will in part be obvi-
30 ous and will in part be hereinafter more fully dis-
closed.

In the drawings which show by way of illus-
tration one embodiment of the invention:

Figure 1 is a front view of a portion of a sewing
35 machine having the improvements applied
thereto.

Figure 2 is a view partly in plan and partly in
section taken above the presser foot.

Figure 3 is a view partly in plan and partly in
40 section showing the throat plate and the fabric
guiding means which cooperates with the guid-
ing wall on the throat plate for guiding the
under fabric section to the stitching mechanism.

Figure 4 is a view in section on the line 4—4 of
45 Figure 2.

Figure 5 is a plan view of the throat plate.

Figure 6 is a section on the line 6—6 of
45 Figure 5 and showing in section one fabric sec-
tion and in dotted lines the other.

Figure 7 is a sectional view through the fabric
sections after they have been joined in a fell
50 seam on the machine.

The machine includes a stitching mechanism
55 having two needles with a looper cooperat-

ing with each needle so as to make two independent
lines of stitching. The material is fed across
the work support by the usual feed dog and is
held on the work support by the presser foot.
5 Located directly in front of the presser foot is
a folder which interfolds the two fabric sections
to form the fell seam. The throat plate is
provided with a recess directly in front of the
needles providing the wall which guides the
10 folded edge portion of the under fabric section.
The presser foot is provided with a recess ex-
tending longitudinally along the underface of
the foot which provides a space for guiding and
directing the interfolded fabric sections and one
15 wall of the recess serves as a guiding means for
the folded edge of the upper fabric section. In
order that these folded edge portions shall be
held in contact with the guide walls provided
therefor, the folder is provided with a finger
20 which extends underneath the folded part of the
under fabric section and contacts with the inner
face of the folded edge portion so as to hold it
against the guiding wall of the throat plate.
The folder is also provided with a guiding mem-
25 ber which extends between the upper section and
the folded part thereof and contacts with the
inner face of the folded edge portion for direct-
ing it along the guiding wall of the presser foot.

Referring more in detail to the drawings, the
30 machine includes a supporting bed 1 on which
is mounted a work support 2. Overhanging the
work support 2 is an arm 3 in which a needle bar
4 reciprocates. Mounted on said needle bar are
two needles 5 and 6. Cooperating with the needle
35 6 is a looper 7 and cooperating with the needle
5 is a looper 8. These loopers are mounted on
a looper carrier 9 which is pivoted at 10 to the
looper support and the looper carrier is moved
back and forth by a link 11. The stitch forming
40 mechanism forms no part of the present invention
and further detailed description thereof is not thought necessary.

The work support 2 is provided with a throat
45 plate 12. Said throat plate 12 has feed slots 13,
14 and 15 through which sections of the feed dog
16 extend for engaging and moving the fabric.
The throat plate is also provided with a slot 17
for the needle 5 and a slot 18 for the needle 6.

Cooperating with the feed and holding the
50 fabric on the throat plate during stitching is a
presser foot 19. Said presser foot is provided
with needle slots 20 and 21 through which the
needles 5 and 6 operate respectively. The presser
foot is provided with a recess 22 on its under-
55

face which extends all the way to the front and the rear of the presser foot and this recess has guiding walls which are substantially in alignment with the outer sides of the needle slots, and the recess is for the purpose of guiding the inter-folded fabric sections during the stitching of the same.

In Figure 7 of the drawings the two fabric sections which are to be joined are shown. One section is indicated at A and the other section is indicated at B. The upper fabric section has its edge portion folded underneath as indicated at a and this provides a folded edge portion a'. The under fabric section has its edge portion folded over as indicated at b, providing a folded edge portion b'. The needle 5 produces a line of stitching indicated at n while the needle 6 produces a line of stitching indicated at n'.

In the fell seaming of these fabric sections it is desirable to place the line of stitching close to the folded edge portion of the fabric section and therefore some means is necessary in order to prevent the folded edge portion from creeping in or creeping out away from the center of the seam and thus producing an irregularly disposed line of stitching relative to the folded edge portion of the fabric section. In order to overcome this creeping of the fabric sections, the throat plate is provided with a recess 23. This recess extends from a point in front of the feed slots 13 and 18 to a point just in front of the needle slots 17 and 18. In order that transverse loopers may be used, the needles are placed in a line diagonal to the line of feed and, therefore, the needle slot 17 is slightly in advance of the needle slot 18. This recess provides a vertical wall 24 which extends from the front of the recess to the rear thereof and terminates adjacent and in front of the needle slot 13. The wall 24 is substantially in alignment with the outside wall of the needle slot 18.

In front of the presser foot is a folder for interfolding the fabric sections to form the fell seam. This folder consists of a supporting plate 25 carrying a scroll member 26. The under fabric section is directed over an extension 27 of the scroll member 26 so that the edge portion thereof contacts with the scroll member and is folded back over on itself. Attached to the supporting plate is an upper folder member 28 which extends over this scroll member 26 where it extends downwardly, thence inwardly and thence again downwardly and outwardly and upwardly so as to form a folding scroll 29. The upper fabric section extends over this upper folder 28 and the edge portion is directed into a channel so that it is undeturned. The scroll member 29 undeturning the edge portion of the upper fabric section and the scroll member 26 overturning the edge portion of the under fabric section are so disposed that these folded parts of the fabric sections are interengaged as clearly shown in Figures 4 and 7 of the drawings. This folder, so far as the folding of the fabric sections to form a fell seam is concerned, is of the usual construction.

The upper folder has a projecting finger 30 which extends beyond the folder parts and to a point adjacent the inner end of the guiding wall 24. The under fabric section is folded over this finger so that the finger contacts with the inner face of the folded edge portion of the fabric section, that is, the inner face of the fabric where it is folded in the forming of the fell seam. This finger serves to hold the folded edge portion of

the under fabric section close up to the guiding wall 24 and insures that the edge portion will not creep to the left relative to the wall so that the needle will pass outside of the folded edge portion. The guiding wall 24 also positively directs the folded edge portion of the under fabric section so that the line of stitching will be located a uniform distance from said folded edge portion. By this positive guiding means for the fabric section, the line of stitching may be placed very close to the folded edge portion of the under fabric section without any danger of the needle stepping over the edge.

The upper folder 28 is also provided with a projecting portion 31 which lies between the undeturned edge portions of the upper fabric section. This projecting portion 31 contacts with the inner face of the folded edge portion of the upper fabric section and it lies close to a vertical wall 32 in the presser foot which guides the folded edge portion of the upper fabric section. This portion 31 will prevent any creeping of the upper fabric section to the right as viewed in Figure 4 so that the needle will step over the edge of the fabric while the guiding wall 32 on the presser foot prevents any creeping to the left as viewed in this figure, and thus the line of stitching made by the needle 5 can be placed very close to the folded edge a' of the upper fabric section and at a uniform distance therefrom.

It will be noted from the above that means has been provided for positively directing the folded edge portions of the interfolded fabric sections during the forming of the fell seam so that these folded edge portions will pass a uniform distance from their respective needles and the lines of stitching will be uniformly placed relative to said folded edge portions. Inasmuch as the edge portions are under positive control at all times, there can be no creeping of the fabric sections so that the needle will step over the edge without penetrating the folded edge portion.

While a two needle stitching mechanism has been shown and described, it is understood that any suitable stitch forming mechanism may be used.

It is obvious that minor changes in the details of construction and the arrangement of parts may be made without departing from the spirit of the invention as set forth in the appended claims.

Having thus described the invention, what I claim as new and desire to secure by Letters Patent, is:

1. A sewing machine for felled seaming comprising spaced needles arranged in a line diagonally of the line of feed, a folder for interfolding fabric sections to form a felled seam, means terminating immediately in front of the needle, stitching the fabric sections adjacent the folded edge in the upper fabric section for positively guiding said folded edge to said needle, and means terminating immediately in front of the needle stitching the fabric sections adjacent the folded edge of the under fabric section for positively guiding said folded edge to said needle.

2. A sewing machine for fell seaming comprising spaced needles, a folder for interfolding fabric sections to form a fell seam, means independent of the folder and contacting with the respective folded edge portions for directing the same to the needles, and means carried by the folder and contacting with said fabric sections respectively at the inner side of the folded edge portions and

in the region where the folded edges of the fabric sections contact with the directing means whereby said edge portions are positively directed to the needles.

5. 3. A sewing machine for fell seaming comprising a work support, a throat plate, spaced needles, a presser foot, a folder for interfolding fabric sections to form a fell seam disposed in front of said presser foot, said presser foot and 10 said throat plate having guiding means for contacting with the respective fabric sections at the folded edge portions thereof for directing the same to the needles, and said folder having means contacting with the respective fabric sections at 15 the inside of the folded edge portions and in the region where the folded edges of the fabric sections contact with the directing means for directing the same to the needles.

4. A sewing machine for fell seaming comprising a work support, a throat plate, spaced needles, a presser foot, a folder for interfolding fabric sections to form a fell seam disposed in front of said presser foot, said throat plate having a recess formed therein providing a guiding wall 20 extending beneath the presser foot to a point in front of and adjacent the needle operating to stitch a folded edge portion guided by said wall, and means carried by the folder and engaging said fabric section at the inner face of the folded edge portion for maintaining said folded edge portion in contact with said guiding wall.

5. A sewing machine for fell seaming comprising a work support, a throat plate, spaced needles, a presser foot, a folder for interfolding fabric sections to form a fell seam disposed in front of said presser foot, said throat plate hav-

ing a recess formed therein providing a guiding wall extending beneath the presser foot to a point in front of and adjacent the needle operating to stitch a folded edge portion guided by said wall, and means carried by the folder 5 and engaging said fabric section at the inner face of the folded edge portion for maintaining said folded edge portion in contact with said guiding wall, said presser foot having a recess in its underface to receive the interfolded portions of the fabric sections and providing a guiding wall for guiding the folded edge portion in the other fabric section.

6. A sewing machine for fell seaming comprising a work support, a throat plate, spaced needles, a presser foot, a folder for interfolding fabric sections to form a fell seam disposed in front of said presser foot, said throat plate having a recess formed therein providing a guiding wall 15 extending beneath the presser foot to a point 20 in front of and adjacent the needle operating to stitch a folded edge portion guided by said wall, means carried by the folder and engaging said fabric section at the inner face of the folded edge portion for maintaining said folded edge 25 portion in contact with said guiding wall, said presser foot having a recess in its underface to receive the interfolded portions of the fabric sections and providing a guiding wall for guiding the folded edge portion in the other fabric section, and means carried by said folder and contacting with the inner face of the folded edge portion of said other fabric section for maintaining 30 said edge portion in contact with the guiding wall on said presser foot. 35

FRANK A. KUCERA.
